ART OF CRACKING HYDROCARBONS

Application filed June 11, 1929. Serial No. 370,096.

This invention relates to improvements in the manufacture of lower boiling hydrocarbon oils, such as gasoline, from higher boiling hydrocarbon oils, such as gas oil, by pressure distillation cracking operations.

The present invention provides a combined operation including a novel heating operation of special value and application in conjunction with pressure distillation, or so-called "pressure shell", cracking operations.

The invention will be described in connection with the accompanying drawings which illustrate, diagrammatically and conventionally, apparatus embodying and for carrying out the invention. In the accompanying drawings, Fig. 1 represents, in elevation and partly in section and with parts broken away, apparatus embodying and adapted for carrying out the invention and Fig. 2 is a fragmentary section through and just above the lower ends of the heating tubes illustrated in Fig. 1.

Referring to the drawings, a stream of high boiling oil is forced, by means of pump 2, through a battery of series connected banks of series connected vertical heating tubes arranged in a vertical heating flue in heating furnace 1 into the vapor separating receptacle 3 from which vapors are taken off under superatmospheric pressure, the oil being heated to a cracking temperature during passage through the heating tubes. The battery of heating tubes consists, as just mentioned, of a plurality of series connected banks 11, 12, 13, 14, 15, 16, 17 and 18 of heating tubes each of which banks consists of a plurality of series connected heating tubes. These several banks of heating tubes are arranged transversely to the general direction of travel of the heating gases entering the upper end of the vertical heating flue in which these banks of heating tubes are arranged so that the heating gases entering the upper end of the heating flue flow across the several banks of heating tubes in succession, first across bank 11, then across bank 12, then across bank 13 and so on, in inverse order with respect to the oil flow therethrough. The heating gases enter the upper end of the vertical heating flue 4 through passage 5 from the firebox

6, in which fuel is burned for supplying heat to the operation, and after passing across and back and across the heating tubes while flowing generally downwardly through the heating flue 4 escape through stack flue 7. The oil flowing through each bank of heating tubes flows successively upwardly and downwardly through the series connected heating tubes forming the bank. The oil supplied to the battery of series connected banks of heating tubes, through connection 8, flows first through bank 18, then through bank 17, then through bank 16 and so on, until discharged from bank 11 through connection 9. Thus, the heating gases from the firebox 6 pass across the upper end of the heating flue 4, as they enter it through passage 5, passing first over the heating tubes comprising the bank 11 through which the oil supplied to the battery of heating tubes last passes, then over the bank 12, then over the bank 13 and so on, and these heating gases then pass generally downwardly through the heating flue 4 over the heating tubes comprising the several banks to the stack flue 7.

The vapors taken off from the vapor separating receptacle 3, through connection 10, are subjected to a refluxing operation in reflux tower 19 from which the vapors remaining uncondensed escape through connection 20 to the condenser 21 arranged to discharge into the receiver 22 from which a condensed distillate product is discharged through connection 23 and uncondensed vapors and gases through connection 24. The pressure in the vapor separating receptacle 3 is maintained and regulated by means of valve 25, or by means of suitable valves arranged beyond the condenser or receiver. Raw oil is supplied to the refluxing operation through connection 26 by means of pump 27, and utilized therein as a direct refluxing medium for effecting and controlling the operation. Admixed reflux-condensate and raw oil are supplied to the battery of heating tubes arranged in the heating furnace 1 from the refluxing operation through connections 28 and 8 by means of pump 2. Residual oil is discharged from the vapor separating receptacle 3 through connection 29.

In initiating operation, oil is circulated from the vapor separating receptacle 3, by means of valved connection 30, through the battery of heating tubes and back to the vapor separating receptacle until normal operating conditions of temperature and pressure are reached, the valve in connection 30 being closed during normal operation. Connection 31, communicating through valved branches with the lower ends of each of the heating tubes, is provided for pumping out the battery of heating tubes at the end of a run. The initial charge of oil, at the beginning of a run, is supplied through connection 32, and the vapor separating receptacle 3 is pumped out at the end of a run through connections 30, 28 and 32. Additional raw oil, in addition to that supplied through connection 26, may be supplied through connection 32 during operation.

In carrying out the invention in the apparatus illustrated, vapors may be taken off from the vapor separating receptacle 3 under a pressure in the general range of 100-300 pounds per square inch, for example, and the oil forced through the battery of heating tubes may be heated therein to a temperature approximately 825-875° F. as discharged through connection 9 into the vapor separating receptacle 3, for example. The rate at which raw oil is supplied through connection 26 may be regulated to condense in the refluxing operation all constituents higher boiling than suitable as components of the desired distillate product, and residual oil may be discharged through connection 29 at a rate regulated to maintain a uniform liquid level in the vapor separating receptacle 3.

In the apparatus illustrated, the vapor separating receptacle 3, the reflux tower 19, and connections 9, 10, 28 and 8 are with advantage thoroughly lagged or thermally insulated.

The heating furnace 1 may, with advantage, be arranged and operated as described in Letters Patent Nos. 1,574,546 and 1,574,547 issued to Sinclair Refining Company, February 23, 1926, on application of the late John E. Bell or as described in Letters Patent No. 1,623,773 issued to Sinclair Refining Company, April 5, 1927, on application of the late John E. Bell.

The present invention has a number of advantages. The combination of vertical oil flow and high velocity oil flow in the heating operation minimizes any tendency toward deposition of pitch or carbon in the heating tubes. The arrangement of the heating tubes is peculiarly compact and permits the use of a gang cleaner with maximum advantage. The heat exchange relations between the heating gases and the oil being heated to a cracking temperature, provided by this invention, are peculiarly effective in pressure distillation cracking operations.

We claim:

In the manufacture of lower boiling hydrocarbon oils from higher boiling hydrocarbon oils, the improvement which comprises forcing a stream of high boiling oil through a battery of series-connected banks of series-connected vertical heating tubes arranged in a vertical heating flue into a vapor separating receptacle, passing heating gases from a firebox in which fuel is burned for supplying heat to the operation across the upper end of said heating flue first in heat exchanging relation with the oil in the bank of heating tubes through which the oil last passes and then in heat exchanging relation successively with the oil in the other banks of heating tubes in inverse order with respect to the oil flow therethrough and then passing the heating gases generally downwardly through said heating flue in heat exchanging relation with the oil in the several banks of heating tubes, and thereby heating the oil to a cracking temperature, and taking off vapors including vapors of the desired low boiling oil from said vapor separating receptacle under super-atmospheric pressure.

In testimony whereof we affix our signatures.

EDWARD W. ISOM.
EUGENE C. HERTEL.
